UNITED STATES PATENT OFFICE.

BERTRAND P. KENYON, OF GRAND RAPIDS, MICHIGAN.

DESIGN FOR A BLANK FOR CASTER-YOKES.

SPECIFICATION forming part of Design No. 34,140, dated February 26, 1901.

Application filed February 2, 1901. Serial No. 45,789. Term of patent 14 years.

To all whom it may concern:

Be it known that I, BERTRAND P. KENYON, a citizen of the United States, residing at Grand Rapids, in the county of Kent and State of Michigan, have invented and produced a new and original Design for Blanks for Caster-Yokes, of which the following is a specification, reference being had to the accompanying drawings, forming a part thereof.

Figure 1 is a plan view of a blank for caster-yokes, showing my new design. Fig. 2 is an edge view of the same.

As shown in the drawings, the leading or material features of my design consist in the substantially straight body portion A and the oppositely and diagonally outwardly and downwardly projecting arms B B, extending from the upper end of the body portion A, thus forming a substantially T-shaped figure with drooping arms. The body A has a recess C at the upper end and a projection D

of corresponding shape at the other end, at each side of which projection are projecting angles or shoulders E. The middle portion of the body is reduced by inwardly-curved outlines F F, as shown, and the arms are curved in outline having convex outer sides and concave inner sides and rounded ends, as shown. Otherwise the surfaces are parallel plane surfaces, as shown in Fig. 2.

Having described my invention, what I claim as new, and desire to secure by Letters Patent, is—

The design for a caster-yoke blank, substantially as described.

In testimony whereof I have affixed my signature in presence of two witnesses.

BERTRAND P. KENYON.
